UNITED STATES PATENT OFFICE.

GEORGE S. WHITE, OF TUGALO, GEORGIA.

CONCRETE-FORM CLAMP.

Application filed July 9, 1925. Serial No. 42,504.

To all whom it may concern:

Be it known that I, GEORGE S. WHITE, a citizen of the United States, residing at Tugalo, in the county of Stephens and State of Georgia, have invented certain new and useful Improvements in Concrete-Form Clamps; and I do hereby declare the following to be a full, clear, and exact description of the invention, such as will enable others skilled in the art to which it appertains to make and use the same.

The invention relates to means for holding in position the form for pouring concrete walls and similar structures.

Under the present practice of pouring concrete walls the forms for the walls are held in position by means of rods secured to the form and after the wall has been poured it is necessary to chisel off the rods and wreck the forms by means of a hoisting engine and a derrick.

This invention provides means by which the forms are securely held in position and after the walls have been poured and it is desired to remove the forms, set screws that are secured through the forms and into the clamping members may be unscrewed from the clamp and the forms taken from the walls to be used again, thus reducing the expense of the building of concrete structures.

To this end the invention has for its object the provision of a clamping member adapted to be anchored in the foundation or in the wall already completed and including a block having a threaded opening to receive the set screw secured through an opening in the form, so that when the wall has been poured and has set sufficiently so that the form may be removed, the set screws may be removed from the clamping member and the form removed from the wall without impairing the form for further use.

The invention will be described in detail hereinafter and will be found illustrated in the accompanying drawings in which—

Figure 1 is a cross section of a concrete structure showing the mold forms in position, and held in place by means of the improved clamping device,

Figure 2 is a top plan view of one of the clamping devices,

Figure 3 is a vertical sectional view on a plane substantially as indicated by the line 3—3 of Fig. 2, and

Figure 4, a view of a modified form of the device.

In the drawings similar reference characters will be used to designate corresponding parts throughout the several views.

A indicates a concrete wall that is being constructed and B the forms for the wall. The forms B are held in position by means of the improved clamping device comprising an eye-bolt 1 that is anchored in the top of the completed wall B. A rod 2 is provided with an eye 3 to engage eye-bolt 1 and is also secured to a block 4 having an opening 5 to receive the end of said rod 2 and the block and rod are secured together by means of a set screw 6. Rod 2 is provided with a plurality of flat faces 7 to form seats for the end of set screw 6.

8 indicates an opening in the form B to receive a set screw 9, said set screw being adapted to engage a threaded opening 10 in the block 4. Set screw 9 has a head 11 adapted to receive a wrench for turning it, and a shoulder 12 that engages a wedge-shaped washer 13 to prevent wear on the part of form B through which the opening 8 extends, the form B being made preferably of timber.

In using the device it will be apparent that after the forms have been set up as shown in Figure 1, the concrete may be poured in between the forms and after the concrete has dried sufficiently to permit removal of the forms, this may be accomplished by unscrewing the set screws 9 and leaving the blocks 4, the rods 2, and eye-bolts 1 in the wall. After removal of the set screws the forms B may be readily removed from the walls to be used again in another location. After removal of the forms, the holes made by the removal of the set screws 9 may be plastered by filling with cement.

In Figure 4 is shown a modification in which rod 2 is provided with a helix 2^a to receive the screw threads on the set screw 9 said threads being cut to engage the coils of helix 2^a. By this construction it will be apparent that the cost of the article will be materially reduced as compared to the cost of production and use of the article shown in Figures 1, 2 and 3, and may be satisfactorily used in certain classes of work. Head 11 may also be provided with a transverse opening 11^a to admit of turn-

ing set screw 9 by means of a bar inserted therein.

What is claimed is:—

1. A concrete form clamp comprising a rod having an end adapted to be anchored inside of a form, a clamp block having two openings therein one of which is threaded, a set screw adapted to engage the concrete form and the threaded opening in the clamp block and means to secure the rod in the other opening of the clamp block.

2. A concrete form clamp comprising an eye-bolt adapted to be anchored inside of a form, a rod having an eye engaging said eye bolt, a clamp block, means to adjustably secure said clamp block to said rod, and a set screw adapted to engage a concrete form and a threaded opening in the clamp block. 15

In testimony whereof I affix my signature.

GEORGE S. WHITE.
